Daniel Simmons

United States Patent Office.

DANIEL SIMMONS, OF NEW YORK, N. Y.

Letters Patent No. 69,496, dated October 1, 1867.

IMPROVED RAILWAY SWITCH.

The Schedule referred to in these Letters Patent and making part of the same.

TO ALL WHOM IT MAY CONCERN:

Be it known that I, DANIEL SIMMONS, of the city, county, and State of New York, have invented certain new and useful Improvements in Automatic Railroad Switches; and I do hereby declare that the following is a full, clear, and exact description of the same, reference being had to the accompanying drawings, making a portion of this specification, in which—

Figure 1 is a partial vertical longitudinal section of a railroad switch and a locomotive, constructed according to or furnished with my invention.

Figure 2 is a horizontal section of the same.

Similar letters of reference indicate corresponding parts in both figures.

This invention consists in a novel arrangement of parts, whereby the operating-bars, after having acted upon the head of one of the levers between the rails, to turn the switch in one direction or the other, as the case may be, are automatically lifted up out of the way, so as not to be interfered with by the head of the other lever when passing over the same.

The invention further consists in a novel means of locking the switch-rails in position, whereby any displacement of the switch is effectually guarded against.

To enable others to understand the construction and operation of my invention, I will proceed to describe it with reference to the drawings.

A indicates the rails of the main track, and B those of the turn-out or side track, while the switch-rails are shown at C, one end, a' , of each of the latter working in the chair in such manner as to allow the requisite lateral movement of the said switch-rails in the operation of the switch, and the free ends of the said switch-rails being connected by a transverse bar, a^* . D indicates two horizontal levers, which are situated between the rails A, nearly or quite in line with each other, and with their innermost ends connected by a vertical pin, b' , each of the said levers being pivoted at or near its centre to one of the ties E, which support the rails, by means of a vertical pivot, C. Formed upon the outer end of each lever D is a head, A^* , the extremity of which is moderately sharp or pointed, as shown at a , in fig. 2, and the side or lateral edges of which are inclined or situated at an angle to each other, as shown at a b in the aforesaid fig. 2. Projecting laterally from each side of the rearmost part of each of these heads A^* is a strong pin, b^* . The innermost end of one of the levers D is connected with the switch-rails C by means of two rods e, the slots e' formed in the inner ends of the said rods, and through which the lever D is passed, being made oblong in order to allow a limited lateral movement of the lever within the slots, the purpose of which will hereinafter appear. Pivoted to the inner side of each of the switch-rails C, and situated in a position transverse thereto, is a pawl, d , the innermost end of which is connected with the same lever D with which the switch-rails are connected, as just set forth, by means of rods d' . Formed in the upper side of a transverse sleeper, F, are two notches $e f$, which are so situated that when the switch-rails C are in line with the rails A of the main track, one of the pawls, d , will catch into the notch e , and thus prevent the switch-rails from being moved inward, except through the agency of the levers D, as will presently be explained, while, when the switch-rails are in line with the rails B of the side track or turn-out, the other pawl will hold in the other notch f , and in like manner prevent the switch-rails from moving inward away from the said side track, any outward movement of the switch-rails in either position being prevented by fixed studs or shoulders g , secured to the tie E, situated at the free ends of the switch-rails, as shown more plainly in fig. 3. The shifting of the switch is produced by the lateral movement of the outer end of either of the levers. Thus the outer end of either lever being moved in one direction, the innermost end thereof is, of course, moved in the opposite direction, and drawing first upon one of the rods d' , lifts the locking-pawl d connected therewith clear from the notch e or f , as the case may be, and then drawing upon the rod e turns or shifts the switch-rails to the desired position, the length of the slots e' , hereinbefore described, enabling the lever to act first upon the pawl to disengage the same before shifting the switch. Situated underneath the rear part of the car or locomotive are two longitudinal bars G, which are placed at a distance apart equal to the width of one of the heads A^* , and the inner edges of which are made convex, as shown in fig. 2. Each of these bars G is attached to the lower extremities of two stems h, which extend upward in suitable bearings provided in the framework of the locomotive, and are acted upon by spiral springs i, which operate to bring the bars G upward to the bottom of the locomotive, as hereinafter more fully explained. I represents two upright bars, of which there is one to

each of the operating bars G, just hereinbefore described, the lowermost end of each of the said upright bars I having shoulders n formed upon it, which rest upon the upper side of the contiguous horizontal operating bar G, and being provided with an extension or downwardly projecting portion n' , which extends down through a longitudinal slot formed in the aforesaid bar G, as shown more plainly in fig. 1. The upper end or portion of each of the said upright bars I is formed with a notch in its front and rear side, as shown at n , and extends upwards through a slot, n' , formed in the platform J, in such manner that when the bar I is pushed downward, one or the other of the notches n , according as the locomotive is running with one end or the other foremost, being caught or fitted upon the shoulder formed at the end of the slot n' , prevents the said bar from rising, and consequently retains the horizontal operating bar G attached thereto in a lowered or depressed position, as indicated in fig. 1. Situated transversely at or about the longitudinal centres of the two upright bars I, one in front and the other in rear of the said bars I, are two fixed rods r , which constitute a fulcrum, upon which the bars I are tilted in the operation of the apparatus, as will presently be fully explained.

As the locomotive approaches the switch one or the other of the upright bars I, according to the direction in which it is desired to turn or shift the switch, is pushed downward until the notch n thereof, catching upon the shoulder formed at the end of the slot n' , through which the said bar is passed, retains the operating bar G connected therewith in a lowered or depressed position, as hereinbefore described, whereupon the advancing movement of the locomotive brings the end of the operating bar G, thus lowered, in contact with one of the inclined sides of the head A^* of the lever D over which the locomotive first passes, and acting upon the said side of the head, turns the lever laterally and operates or shifts the switch, as hereinbefore explained, which being done the projection n' of the upright bar strikes the laterally projecting pin b^* situated upon the aforesaid side of the head A^* , which tilts the bar I upon the fulcrum formed by the transverse rods r , and consequently brings the notch n away from the shoulder formed at the end of the slot n' , whereupon the springs i force the operating bar G upward against the under side of the frame of the locomotive, so that it will not be interfered with by the other or opposite lever D when passing over the same. Inasmuch as the inner ends of the levers D are pivoted together, the switch may be operated with equal facility by the action of the operating bars G upon the head A^* of either of the said levers, so that the switch may be automatically shifted by the locomotive when advancing in either direction.

What I claim as my invention, and desire to secure by Letters Patent, is--

1. The horizontal operating bars G, upright bars i, stems h, and springs I, arranged to operate in relation with each other and with the platform J, fulcrum r, and the laterally projecting pins or studs b^* of the lever-heads A^* , substantially as and for the purpose herein set forth.
2. The combination of the locking pawls d and rods d' , with the switch-rails C and levers D, substantially as and for the purpose herein set forth.

DANIEL SIMMONS.
